UNITED STATES PATENT OFFICE

LILLY DAIGRE-GORE, OF NEW ORLEANS, LOUISIANA

DESIGN FOR A SMOKER'S STAND OR SIMILAR ARTICLE

Application filed July 7, 1930. Serial No. 36,292. Term of patent 14 years.

To all whom it may concern:

Be it known that I, LILLY DAIGRE-GORE, a citizen of the United States, and a resident of New Orleans, parish of Orleans, and State of Louisiana, have invented a new, original, and ornamental Design for Smoker's Stand or Similar Article, of which the following is a specification, reference being had to the accompanying drawings, forming a part thereof, wherein the thickness of the body portion of the article is substantially in natural proportion to the height and width thereof, and wherein—

Figure 1 is a front view of the smoker's stand or similar article showing my new design, and,

I claim:

The ornamental design for a smoker's stand or similar article, as shown and described.

In testimony whereof I affix my signature.

LILLY DAIGRE-GORE.
